UNITED STATES PATENT OFFICE

172,300

CORNER CLEANER

Anna Penzato, New Paltz, N. Y.

Application October 15, 1953, Serial No. 27,186

Term of patent 3½ years

(Cl. D9—5)

To all whom it may concern:

Be it known that Anna Penzato, a citizen of the United States of America, residing at New Paltz, New York, in the county of Ulster and State of New York, has invented a new, original, and ornamental Design for Corner Cleaner, of which the following is a specification, reference being had to the accompanying drawing, forming part thereof.

Figure 1 is a perspective view of a corner cleaner embodying my new design.

Figure 2 is a plan view thereof.

Figure 3 is a side view thereof.

Figure 4 is a front view thereof.

I claim:

The ornamental design for a corner cleaner, as shown.
